EMBROIDERY AID AND FRAME

Robert Salz, Hollywood, Calif., assignor to Highland Art Embroidery Company, Pasadena, Calif., a partnership

Application February 24, 1948, Serial No. 10,449

2 Claims. (Class 40—152)

1

This invention relates to an embroidery device having an educational and amusement value and serving the double function on an embroidery hoop and a picture frame.

Embroidery is generally done on a piece of cloth having a printed pattern as a guide for embroidery. When working thereon the cloth is generally stretched across an embroidery hoop. The conventional embroidery hoop comprises a pair of circular bands disposed one inside the other, when in use, to bind the cloth therebetween and stretch it taut across the circle. After the embroidery is completed it is generally removed from the hoops and washed and thereafter framed or the like.

The present invention provides means, particularly adapted for use by children, whereby the print carrying embroidery cloth is bonded between two cooperating frames which serve as an embroidery "hoop" and thereafter as a frame for the completed embroidery which may be hung on the wall or the like. The device is so constructed that the whole assembly, including the embroidery cloth, may be washed after completion of the art work and prior to hanging. This double aspect of the device of the invention is of particular advantage in providing an educational amusement device for children. The embroidery cloth being rigidly stretched between the frames may be worked on continuously or periodically until the art work is completed and it may then be washed and hung in the child's room.

Many modifications in the invention will be obvious from the description. Thus elaborate patterns and frames may be employed to adapt the device of the invention to adult embroidery and to present a sufficiently pleasing appearance to justify display of the completed work in the frame provided.

The invention will be better understood from the following detailed description thereof taken with respect to the accompanying drawing in which:

Fig. 1 is an isometric elevation view of the device of one embodiment of the invention;

Fig. 2 is a sectional elevation taken on the line 2—2 of Fig. 1;

Fig. 3 is a sectional elevation showing the use of wooden frames having identical openings but differing in cross section; and

Fig. 4 is a sectional elevation showing an alternative frame combination.

Figs. 1 and 2 illustrate a simple embodiment of the invention comprising two identical frames 10, 11 joined together back to back with a piece of

2

embroidery cloth 12 stretched therebetween and bonded between the frames along the edges thereof.

To permit washing the embroidery work without removing the cloth from the frames, the ability to do which is a feature of the invention, the cloth is bonded between the frame edges with a water-insoluble glue 13. Innumerable glues of this type are known including the polymerized resins, animal glues, casein, liquid rubber glues, fish glue and the like. The only limitations in glues suitable for use in the present invention are (1) moisture resistance, and (2) sufficient heat resistance to permit immersion of the device in hot water.

The cloth 12 may be of substantially any type suitable to receive embroidery work such as for examples, unbleached muslin, unbleached sheeting, unbleached linens, etc.

The frames 11, 12, although shown in Figs. 1 and 2 as being identical, do not necessarily have to be identical. Thus as shown in Fig. 3, the rear frame 14 may have a simple rectangular configuration when viewed in section and the front frame 15 may have a curvilinear front face for decorative purposes. For purposes of uniformity, however, it is desired that the frames have the same size openings and that they be of the same width, so that when bonded together they will appear as a single frame in which the cloth is embedded.

The frame openings may be of substantially any size and shape. Although rectangular frames are generally more popular the device of the invention may incorporate circular, oval or even irregular frames providing that the two frames are substantially identical in configuration (when viewed in elevation).

Furthermore, the frames may be made of plastic as shown in Figs. 1 and 2, or other materials such as wood shown in Fig. 3, or even metal or other water-insoluble material. The type of plastic employed in making the frames is limited only in that it must be water-insoluble and heat resistant so as to permit washing thereof in comparatively hot water and is further limited by economical factors. Thus as a child's educational or amusement device, it is recommended that the frame be made of comparatively inexpensive plastic, but on the other hand for more elaborate frames for adult use, which have a potentially longer useful life, more expensive materials may be employed. In using wooden frames, as shown in Fig. 3, the wood of these frames is

coated with a water insoluble lacquer or varnish so as to make them water resistant.

A modified type of framework is shown in Fig. 4. In this embodiment one frame 17 has a continuous peripheral bead 19 extending around its inside face and the other frame has a corresponding peripheral groove 18 into which the bead 19 is adapted to fit. The bead and groove arrangement serves the double purpose of firmly anchoring the cloth between the frames and of insuring proper alignment of the two frames during assembly of the device.

As is well known in the embroidery art, the patterns on the embroidery cloth 12, may be of unlimited variation. Similarly, the type of ink employed to outline the pattern may be of substantially any kind, preferably water insoluble, so as to prevent discoloration of the embroidery upon washing.

A shrinkable cloth is preferred so that after washing it will be stretched tightly between the frames.

The embroidery device of the invention is not only educational, constructive and entertaining, particularly with reference to use by children, but is also intensely practical for the elimination of embroidery hoop and the provision of integral framing means serving the double function above referred to.

This dual function is of particular merit with respect to the use of the apparatus by children in that it eliminates the necessity of proceeding through a number of stages including insertion in conventional embroidery hoops, the removal therefrom, washing, and mounting in a frame or the like. The child will take a great deal more interest in art work if provision is made for displaying the same upon completion, this provision, being inherent in the device of the invention, insures the satisfaction of this desire which as above mentioned, is not limited to children.

Many modifications in the configuration of the framework and other features of the device of the invention may occur to those skilled in the art without departing from the scope thereof as defined herein.

I claim:

1. An educational toy comprising washable first and second frames, each frame defining an opening of substantially the same area and configuration as the other frame, a piece of cloth smaller than the outside of the frames and larger than the opening, waterproof adhesive means permanently bonding the outer edges of the cloth between the two frames to permanently bond the frames and the cloth together to hold the cloth stretched across the opening whereby embroidery may be placed on the cloth and the embroidered cloth washed in the frame.

2. An educational toy comprising first and second waterproof and heat resistant frames each defining an opening of substantially the same area and configuration as the other, a piece of cloth smaller than the outside of the frames and larger than the opening, waterproof and heat resistant adhesive means permanently bonding the outer edges of the cloth between the two frames, the frames being thus permanently bonded together cooperating to hold the cloth stretched across the opening, whereby embroidery may be placed upon the cloth and washed in warm water in the frame.
